UNITED STATES PATENT OFFICE.

DENNIS FRISBIE, OF NEW HAVEN, CONNECTICUT, ASSIGNOR TO HIMSELF AND SAMUEL C. GOODSELL.

IMPROVEMENT IN HOISTING APPARATUS.

Specification forming part of Letters Patent No. **58,340**, dated September 25, 1866.

To all whom it may concern:

Be it known that I, DENNIS FRISBIE, of New Haven, in the county of New Haven and State of Connecticut, have invented a new and useful improvement in the mechanism for shifting the load on the arms of cranes; and I do hereby declare that the following is a full, clear, and exact description of the construction and operation of the same, reference being had to the annexed drawings, making part of this specification, in which—

Figure 1 is a perspective view. Fig. 2 is a side elevation of the shifting mechanism, and Fig. 3 is a plan of the same.

In the several figures the same letters are employed in representing identical parts.

My improvement relates to a device for shifting the load raised by the rope or chain of a crane from the post toward the outer extremity of the arm, or vice versa, and the following description will enable a person versed in the art to construct the same.

A represents the post, and B the horizontal arm of the crane. The arm is composed of two pieces of timber placed parallel to one another and having a space left between them, the upper surface being made smooth.

C is the frame supporting the weight attached to the pulley P, and carrying the gearing by which it is actuated. This frame is supported upon four truck-wheels, D, which have flanges upon their inner sides and run upon the inner edges of the upper faces of the timbers forming the arm B. E is a pulley placed upon the overhung extremity of the shaft F, and is turned by the gearing-chain E'. Upon the opposite extremity of the shaft F, also overhung, is placed a spur-wheel, G, geared into the spur-wheel H on the extremity of the shaft I, the journals of which are on the center of the frame. The wheel H is larger than the wheel G when it is desired to increase the power. On the opposite end of the shaft I is a pinion, K, working into the

rack L, which is attached securely to the arm B. This arrangement of the gearing enables the operator by means of the gearing-chain E' to cause the frame C to traverse the arm B as desired.

The weight is suspended from a stirrup, P', attached to the pulley P by rope or chain Q, which is attached to the cross-piece at the end of the arm B. This chain is shown in blue on the drawings, and is carried over a pulley, M', suspended by hangers below the top of the arm B. These hangers form part of the frame C. The chain Q is then carried under the pulley P and over the pulley M, which corresponds to the pulley M'. It is then carried over a pulley, O, attached to or near the post A, and thence to the hoisting apparatus. The weight being suspended below the frame the latter is by it retained in place, and as the pulleys M and M' are on each side of and equidistant from the middle of the frame C, the weight is equally distributed on the four truck-wheels D.

As the pulleys M M' and P all turn freely, it follows that the frame C, and with it the load, may be freely moved along the arm B as desired.

What I claim as my invention is—

The traversing frame C when supported by the truck-wheels D running on the horizontal arm B of a crane, and moved by the pulley E through the spur-wheels G and H and pinion K and rack L, and bearing suspended the load, attached to the movable pulley P, from pulleys M and M', over which the chain Q passes, said several parts being arranged substantially as set forth.

In testimony whereof I have signed my name to this specification in the presence of two subscribing witnesses.

DENNIS FRISBIE.
